DIRECT LIGHTING FIXTURE

Leroy C. Doane, Meriden, Conn., assignor to The
Miller Company, Meriden, Conn., a corporation
of Connecticut

Application February 6, 1936, Serial No. 62,601

9 Claims. (Cl. 240—78)

The present invention relates to direct lighting fixtures and more specially to direct lighting fixtures employing two light sources.

The present invention contemplates a lighting fixture adapted to use incandescent lamps and mercury vapor lamps, both burning in pendant positions.

As the heat generated by the operation of all these lamps is considerable, it has been found necessary to take special precautions to properly cool the lamp sockets and the upper part of the vapor lamp so as to secure proper operation for the vapor lamp.

The present invention therefore provides a holder for the lamp bulbs and sockets having suitable ventilation features whereby the heated air is dissipated without causing an undesirable rise in temperature of the holder and parts carried thereby.

In effecting the control of the heated air rising from the lamp bulbs, the present invention makes use of a baffle apertured to receive the lamp bulbs and held in a holder in such a way as to permit the hot air to spill around the edges of the baffle and pass into the upper part of the holder, this part being skeletonized so that the hot air readily escapes to the outside atmosphere. The accompanying drawing shows, for purposes of illustrating the present invention one of the many embodiments in which the invention may take form, it being understood that the drawing is illustrative of the invention rather than limiting the same.

In the drawing:

Fig. 1 is a vertical sectional view of a direct lighting fixture on the line 1—1 of Figs. 2 and 3, with parts in elevation and parts broken away;

Fig. 2 is a sectional view on the broken line 2—2 of Fig. 1, with parts in elevation;

Fig. 3 is a section taken on the line 3—3 of Fig. 1 looking in the direction of the arrows;

Fig. 4 is a perspective view of the holder and bulbs, the enclosure being omitted; and

Fig. 5 is a fragmentary vertical section on the line 5—5 of Fig. 3.

The fixture shown herein is adapted to be supported in a pendant position by a pipe, conduit or other support 10. The holder 11 is threaded onto this pipe and supports the fixture. The holder, as shown in the drawing, has a comparatively small upper annular portion 12 and a plurality of downwardly extending ribs or straps 13 secured to an intermediate flat portion 14. This flat portion is apertured as indicated at 15 in Fig. 2. The holder is provided with down-

wardly extending straps or ribs 16, 17, 18, all of which support a lower annular large diameter skirt portion 19. The holder is preferably in the form of a casting.

A central pendant lamp socket 20 is secured in the upper part of the holder and adapted to be connected by wires indicated at 21 with a current source. This socket supports a pendant mercury vapor lamp 22 whose electrodes are indicated at 23 and 24. The flat portion 14 of the holder supports three lamp sockets 25 which carry incandescent lamp bulbs indicated at 26.

The incandescent lamp sockets 25 are connected to wires 27 passing through an annular wireway, as indicated at the right of Fig. 1. These wires are held in place by narrow segments 28 secured to the lower face of the holder by screws 29. The ends of the segments are spaced, as indicated at 30, Fig. 2, to facilitate the wiring, and the ends of the segments are held in place by the lamp sockets.

The upper portion of the current supply wires for the incandescent lamps is indicated at 31. They pass down through a channel-shaped rib 32 and are held in place by a cover indicated at 33. The ends of this cover are bent, as shown in the drawing, and the cover is held in place by the sockets.

The vertical ribs 18 are made thick, as indicated at the left of Fig. 1, while the ribs 16 and 17 are thinner. These thick ribs provide inwardly extending lugs 34 which are tapped to receive screws 35. These screws support a baffle plate 36. The outer edge of this baffle plate is indicated at 37, and it will be apparent from the drawing that the edge of the plate is spaced from the walls of the holder so as to form channels or vents for the escape of the heated air.

The straps 16 are apertured, as indicated at 40, to receive the upper ends of hook members 41. The lower ends of these hook members are indicated at 42, and they are adjustably secured in place by thumb screws indicated at 43. The peripheral flange on the baffle plate 36 is notched to accommodate these screws.

The straps 41 form a convenient shade support for securing any form of enclosing shade about the bulbs. This shade may be merely an all-metal reflector of any desired shape, or may be combined diffusing glass enclosing globe, as indicated at 45 and metal reflector indicated at 46. Whatever form of enclosure is employed, it has a tendency to confine the heat generated by the lamps and to make it necessary to ventilate the holder. The heated air will pass up through 55

the peripheral vents about the baffle plate, and owing to the large openings in the holder, this air will readily escape to the outside atmosphere.

It will thus be apparent that there will be a minimum heating of the sockets, wires and terminals and of the upper part of the mercury vapor lamp. The lamp can be kept cool enough to properly function.

It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

What is claimed is:

1. A direct lighting fixture comprising a central downwardly opening lamp socket, a pendant mercury vapor lamp carried therein, a plurality of downwardly opening lamp sockets circumferentially disposed below the central socket, incandescent lamps in the latter mentioned sockets, a common support for all the sockets, said support being in the form of a skeletonized holder 25 to provide ventilation about the sockets, a lamp enclosing member carried by the holder and disposed about the lamps to cause air heated thereby to pass upwardly through the member and the holder, and a baffle plate mounted below the 30 sockets and apertured to receive the upper portion of the lamps and having its edge spaced from the holder to provide a peripheral ventilation space whereby the heated air within the member is diverted from the upper end of the vapor 35 lamp and its supporting socket, and passes out through the holes of the skeletonized holder.

2. In a direct lighting fixture, a downwardly opening central socket, a plurality of downwardly opening sockets spaced circumferentially outside 40 and below the central socket, an annular downwardly opening socket holder to which all the sockets are secured, the holder being skeletonized to afford free escape of heated air and having a skirt about its lower edge, lamp bulbs in the 45 sockets, a partition wall across the holder below the sockets and above the skirt, the wall being apertured to receive the upper portions of the lamp bulbs and of smaller diameter than the holder to facilitate escape of air upwardly between the edge of the wall and the holders, and a lamp enclosing member secured to the skirt of the holder.

3. In a direct lighting fixture, a pendant mercury vapor lamp, a supporting socket, a socket 55 holder, a horizontal plate apertured to receive the vapor lamp and disposed above the upper electrode of the vapor lamp, a plurality of circumferentially disposed lamp sockets carried by the holder below the first socket and above the 60 plate, incandescent lamps therein, the necks of these lamps passing through apertures in the plate, the peripheral edge of the plate being spaced from the lower portion of the holder to

facilitate the passage of heated air up between the edge of the plate and the holder, the holder being provided with large ventilation apertures above the edge of the plate to facilitate escape of heated air from the fixture, and a lamp enclosing member supported from the holder.

4. In a direct lighting fixture, a holder having an upper small diameter portion and a lower large diameter portion, both portions being provided with large ventilation openings to allow free flow 10 of air, a central downwardly opening socket in the upper portion, a plurality of downwardly opening sockets in the lower portion, a partition wall supported below the sockets and apertured for lamp bulbs carried in the sockets, a mercury 15 vapor lamp in the first socket, incandescent lamps in the other sockets, the edge of the partition wall being spaced from the holder to provide peripheral air vents.

5. In a lighting fixture, a socket holder having 20 upper, intermediate and lower annular portions interconnected by spacing ribs which provide laterally opening ventilation openings, a central socket secured to the upper portion, a plurality of sockets secured to the intermediate portion, 25 an apertured plate secured to the lower portion with its edges spaced therefrom to provide peripheral air vents, and socket supported lamps projecting through the apertures in the plate.

6. A lighting fixture such as claimed in claim 5, 30 wherein the intermediate portion of the holder is flat and provided with ventilation apertures.

7. A lighting fixture such as claimed in claim 5, 35 wherein the holder has an annular wire receiving channel for the lower sockets and a cover for said channel.

8. In a pendant lighting fixture, a holder having an annular shade receiving skirt, internally disposed lugs spaced above the lower edge of the skirt, an annular baffle plate fitting the lugs and 40 spaced from the holder walls to afford vents, means to secure the baffle plate in place, shade supports carried by the holder, sockets above the plate, and bulbs in the sockets projecting through apertures in the plate, the holder being skeletonized above the plate to prevent hot air accumulating about the sockets.

9. In a lighting fixture, a downwardly opening stepped, bell shaped holder having an upper small diameter portion, a central socket carried thereby, an intermediate, flat portion connected to the upper portion by ribs and provided with an annular wireway-forming groove, circumferentially disposed sockets carried by said intermediate portion, a sectional cover plate for the groove, one of the ribs being grooved to form a wireway leading to the first groove, a cover plate for the last mentioned wireway, wiring for the central socket, and independent wiring disposed in said groove and connected to the circumferentially disposed 60 sockets.

LEROY C. DOANE.
